STRIP FEEDING MECHANISM

Alvin F. Groll and Meredith R. Hatch, Toledo,
Ohio, assignors to E. W. Bliss Company, Brook-
lyn, N. Y., a corporation of Delaware

Application November 4, 1941, Serial No. 417,868

39 Claims. (Cl. 153—54)

The present invention relates to a mechanism for uncoiling metal strip from reels which are placed in a coil cradle and for flexing said strip while it is fed through a plurality of rolls to a feeding station to be acted on.

In handling heavy metal coils of large diameter it is a serious difficulty to get the coil promptly placed and adjusted in the cradle without losing control over its movement during the operation. It has been, therefore, one of the objects of the invention to provide means which enable the operator to move the coil onto the cradle and adjust it therein smoothly and without heavy jolts.

Another object of the invention has been to provide a novel flexing mechanism comprising a plurality of rolls through which the strip is fed while being uncoiled and which serves the purpose of producing a mechanically uniform metal structure and of eliminating any unevenness in said structure which may have formed in some earlier stage of the fabricating process.

A further object of the invention has been to provide improved control mechanisms for regulating the delivery of the strip from the coil and in general the feed through the device in accordance with the demands of the operations, said control mechanisms consisting partly in hydraulic and partly in electric means as will appear hereafter in the detailed description, all of said means contributing to provide mechanism for handling strip at high speeds.

Where the expression "strip" is used throughout the specification and claims it is meant to indicate sheet metal of any desired width.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:

Fig. 1 is a side elevation of the machine with some parts broken away;

Fig. 2 is a view similar to Fig. 1, the upper coil cradle being removed; the figure shows some parts in greater detail and on an enlarged scale;

Fig. 3 is a section on line 3—3 of Fig. 2;

Fig. 4 is a plan view of the cradle rolls and driving mechanism therefor, partly in section taken on lines 4—4 of Fig. 1;

Fig. 5 is a side view partly in section on lines 5—5 of Fig. 4 of the cradle showing a part of the coil about to be placed thereon;

Figs. 6 and 7 are similar views showing later stages in the placing of the coils on the cradle;

Fig. 8 is a diagrammatic illustration of the hydraulic operating system; and

Fig. 9 is a wiring diagram of the electric control system.

The apparatus generally comprises a pair of coil cradles, one mounted above the other. Each of the cradles is power driven to feed strip material through the usual scrubbing rolls to breaker rolls by which the grain of the strip is broken. After the strip leaves the breaking rolls it is fed through a series of rolls and finally passes a sheet feeding device into the particular machine tool which is to operate on the material. This tool may be a metal working press, for example, by which the strip is drawn into a fabricated article, such as automobile fenders or the like.

Referring now to Fig. 1 of the drawings there are shown a pair of reels, the lower being numbered 11 and the upper 12. In the case of the former, strip is fed over the top as indicated in Fig. 1, into the feeding rolls. On the other hand, strip is fed on the upper cradle downwardly beneath the feeding rolls. In this way there is provided an easy manner of feeding strip from either cradle to a common point, after which the actual feeding operation takes place.

It is intended that one cradle shall be employed at a time and that after the strip loaded thereon has been removed the second cradle is called into play while the first is being replenished with stock for feeding.

In order to facilitate the feeding of the strip from the cradles a series of small rolls *a* are provided which are mounted on one of two supports 18 (Fig. 1). One set of rolls is provided for each cradle.

In initially setting up the apparatus for feeding the operator will manually pass the end of the strip from its supporting cradle to the feed rolls, during the course of which the strip will rest on one or the other sets of guide rolls *a*. In Figs. 1 and 2 the lower cradle is shown as being in operation while the unused strip from the upper cradle is positioned between the rolls 20 and 21 in position to be fed when desired.

The rolls 19 and 20 which receive the strip from the lower cradle and the rolls 20 and 21 which receive the strip from the upper cradle are brushing rolls which act to remove scale and

dirt from the same before it passes further through the apparatus. Succeeding rolls 22, 23 and 24 grip the strip to draw it through the respective aforementioned brushing rolls.

To initially mechanically feed the strip the rolls 23 and one of the two rolls 22 or 24 are employed. These latter two rolls are journaled in supports 26 and 27 respectively (Fig. 2) of a pair of frame members 28, which pairs are in turn journaled on the main frame at 29. Thus, depending on the adjusted position of the members 28, the lower strip may be gripped and fed by the rolls 22 and 23 or the upper strip may be gripped and fed by the rolls 23 and 24. To this end the roll 23 is power driven and effects a driving action on the strip by frictional engagement with one of its cooperating rolls.

A second pair of power driven feed rolls are provided and are numbered 30 and 31 respectively. These rolls, each being journaled in the machine frames 14, are maintained in the same relation with regard to each other and act to feed strip irrespective of the adjusted position of the rolls 22 and 24. In order to control the tendency of the strip improperly to unwind from the upper coil a holding roll 25 (Fig. 1) is provided. The lower coil, by reason of the position of its cradle is not subject to this tendency.

The feeding of the stock from the cradles to the breaker is controlled by a switch 126, for the upper cradle, and a switch 127 for the lower cradle. The electric connections by which these function will be hereinafter described.

A flexing mechanism comprises a part of the present apparatus and this is best shown in Fig. 2. This includes a further feed roll 35 of comparatively large diameter which is rotatably mounted in the machine at 36 and is power driven during the time of threading the machine. The drive to this roll is then released by a clutch. In cooperation with the roll 35 are two small rolls 37 and 38 which act as pinch rolls for the metal strip. A guide shoe 40 pivotally mounted on the frame at 41 is employed to hold the strip against the roll 35 during the time when a sheet is initially passed through the apparatus preparatory to continuous feeding. This shoe may be released during continuous feeding by means of a cam mechanism 47.

The flexing mechanism proper consists of rolls 35 and 50 and two sets of breaker rolls c and d, one set being disposed above the other for cooperation therewith. The rolls of the upper set are, as shown in Fig. 3, mounted between frame bars 42, one at each side of the machine. These parts in turn carry drive shafts 43 having worms 44 fixed thereto. The worms drive worm gears 45 which are threadingly engaged with eye-bolt members 49 secured to the bars 42 supporting the upper breaker rolls. Worm gear shafts are adapted to be engaged by cranks to permit vertical adjustment of the upper set of rolls.

The lower set of breaker rolls is mounted in a frame 164 which is pivotally carried by a shaft 51. On frame 164 is a link 165 pivotally mounted at 166 and journaled at the other end in a block 167. The blocks in turn support a piston rod 168 at a threaded connection 169, the piston being received in a suitable cylinder. Oil under pressure may be supplied to the cylinder, as hereinafter described, by a solenoid D to control the operation of the breaker mechanism.

The purpose of this piston mechanism is to permit the lower breaker rolls to be dropped to

open a passageway for introducing the metal strip to the machine at the time a new strip is supplied and when the machine is stopped. By pulling the piston rod 168 to the right, block 167 is likewise moved, link 165 is pulled to the right as well and this causes the frame 164 to be rocked about its pivot and lowered, disengaging the two sets of breaker rolls.

The second large rolls corresponding in size to the roll 35 and likewise power driven is indicated in Fig. 2 at 50, this roll being rotatably mounted at 51 with the frame 164. As the strip leaves the flexing mechanism and the breaker rolls it is engaged by the roll 50 and fed on through the apparatus. Such further feeding is accomplished by two pinch rolls 52 and 53, respectively mounted on top and bottom of the roll 50 and in tight engagement therewith. The clutch to roll 50 may now be disengaged. A guide shoe 54, corresponding to the shoe 40 only mounted in a fixed position, used for the same purpose, is provided to cooperate with the roll 50.

In a plane below the flexing mechanism are two curved guide bars 56, one of which is shown in Fig. 2. One end of this bar is pivotally mounted at 57 whereas the other end carries an L-shaped member 58 which is hooked into a loop of a belt 60, the latter being adapted to be wound up manually on a roll 59 by means of a crank or the like. As shown in full lines, the guide bar is in the position which it takes when the feeding of strip through the machine is started; at this time it serves as a guiding member for the strip after this leaves roll 50, and before the strip reaches a pair of brushing rolls e and successive gripping rolls f which serve for gripping the metal strip and passing it on to a set of straightening rolls g. As soon as the strip arrives at and is taken up by these rolls, the guide bars are returned to the position shown in dotted lines where they remain until the next feeding operation starts.

After the strip has passed the straightening rolls g it is fed out of the machine by feed-out rolls h. Besides the sets of rolls enumerated above a pair of guide rollers 61 are provided at the delivery side of the machine, serving as a guide against lateral displacement. Moreover, there are two limit switches, N and M, one serving to slow down the speed of the strip as the strip opens said normally closed switch N, the other to completely stop the end of the strip as soon as it has arrived at the following operating station. During the time of press operation the strip from the cradle through the breaker and up to the straightening and feed-out rolls will travel at a slow rate of speed. These above mentioned switches are part of electrical circuits, which will be described in connection with the wiring diagram of Fig. 9.

Three limit switches P, R and Q are also provided beneath the flexing mechanism, which control the speed of the strip as it is fed through said breaker mechanism. The action of these switches 65 will likewise be more fully explained later.

Since the construction of both coil cradles is the same, only one of the cradles has been shown in detail in Figs. 4 to 7 and will now be described with reference to these figures. The cradle is mounted on the machine frame 14 and comprises two circular plates or disks 70 which serve to accommodate the metal coils between them. These disks are adjustably mounted on threaded shafts 71 so that coils of varying widths may be carried by the cradle. The adjustment is made by means

of nuts 72 which are moved forth or back on shafts 11 by a driving mechanism 73 to which they are connected by an endless chain 74, engaged with sprockets 78 and 79.

The driving mechanism 73 comprises a gear 75 meshing with a pinion 76, which is driven by a separate electric motor. A clutch connection 11 is used between the drives of both ends to allow individual adjustment of either end. The drawing shows the clutch in the engaged position. Both adjusting mechanisms at the opposite ends of the cradle are connected by a shaft 79^a, both nuts 72 can thus be driven in unison.

Extending from the drive end to the center of the cradle are two driving shafts 80 journaled in and extending through supporting tube 81^a and journaled into the end of fixed support shaft 84^a at 88. The support tube 81^a and shaft 84^a are secured to the machine frame 14 at the outer ends by bearing brackets 89 and at the inner ends by bearing brackets 89^a, and these brackets are bolted to part of the frame 14^a. Each of the shafts 80 has a gear 81 mounted thereon and the gears are driven by a common pinion 82 meshing with both of them. The pinion in turn is driven by one of two hydraulic motors 120 or 121 respectively (see Fig. 8).

Within the machine frame intermediate the disks 78 eight carrying members or links 88 are provided, which are supported by tubes 81^a and shafts 84^a.

Bushings 82^a and 83^a are interposed between the driving shaft and the tube 81^a in order to provide clearance for independent rotation of said parts. Shaft 80 is provided with a shoulder 91 which carries a pinion 92 engaging with a gear 93 at either side.

These last mentioned gears are keyed on shafts 84, which are journaled in the carrying members 88, so as to be rotatable therein; carriers 88 are in turn pivoted on tubes 81^a and shafts 84^a. The shafts 84 are driven by gears 93 when pinion 92 is rotated by means of the above mentioned driving mechanism. The rolls 95 for carrying the coil are mounted on said shafts. Gears 93 are made in halves allowing the key to be removed, shaft 94 pulled out endwise and roll 95 removed for resurfacing.

Each roll carrying shaft 94 carries four rolls which are placed at approximately regular intervals along said shafts. Since these rolls are of known construction it is not necessary to describe them in detail except to say that they cooperate to provide a rolling support for a coil thereon.

The mechanism for easily transferring a coil to the rollers 95 when the apparatus is to be loaded is best shown in Figs. 5, 6 and 7. This mechanism includes the carrying members 88 which consist of an end plate 87 and a portion 96 projecting therefrom and being shaped to accommodate the rollers 95 over part of their length.

The coil adjusting mechanism moreover comprises two hydraulically operated elevators 100 arranged along the center line of the cradle adjacent to the innermost rolls thereof. These elevators 100 each consist of a cylinder 101 with an oil supply pipe 102 connecting it to a reservoir (not shown) from which it may receive oil under pressure. A piston 104 is slidably mounted in a sleeve 103 closely fitted to the top of cylinder 101, and is exposed at its end to the oil pressure in the cylinder. The piston includes a shoulder 105 at the bottom end which locks it against an abutment in sleeve 103, thus limiting its up-

ward movement. When the piston is in this position it is completely extended and is in substantial alignment with a platform 106 of the machine frame. The top part of the piston 107 is square shaped as shown in Fig. 4, with the edges projecting beyond the periphery of the piston walls. The surface of this top piece is slightly concave to generally correspond with the periphery of the coil during loading of the same (see Fig. 6, in which the coil is about to be moved onto said top piece 107). A shoulder is cut into a part of the top piece, the purpose of which will be later explained. Piston 104 is closely fitted into the sleeve 103 by means of a packing nut 108 and a ring of suitable packing material. Fig. 7 shows the piston in retracted position.

A third portion of the loading mechanism designed to cooperate with the carrying members 88 and the pistons 104 in the adjustment of the coil comprises two rocking members 111, which are shown in different positions in Figs. 5, 6 and 7. These members are substantially triangular in shape and are pivotally mounted at the apex on shafts 81^a and 84^a. Both sides of said rocking members are shaped to form flanges 114 and 115 which engage with correspondingly formed recesses 112 in frame 106 and shoulder 108 in top squares 107 of the portions 104 respectively. A semi-circular slot 111^a is provided on said members which allows them to drop to a lower position when the flanges 114 and 115 are disengaged, as shown in Fig. 7.

The operation of this coil loading mechanism is as follows. When the coil cradle is ready to receive a new coil a truck or the like will be placed close to platform 106 for delivering the new coil onto the cradle. At this time member 111 will be placed so as to lie in alignment with platform 106 by raising the piston which supports member 111 at the right-hand end, the left-hand flange 115 fitting into recess 112. As it is rolled from the platform to member 111 the coil presses down the left-hand set of rolls 95 to the position shown in Fig. 5. It will be understood that the member 111 forms a guideway for the coil during its passage over the rolls until it reaches its final position. As soon as the coil has pressed down the second set of rollers and is about to pass the center of the cradle it will come to rest on the piston top 107 which has previously been raised to support the substantial alignment of member 111 with platform 106 (Fig. 6). When the coil rests on 107, the piston 104 will be lowered to take the position shown in Fig. 7, the coil being passed on to the rollers of the right-hand set, where it finally reaches a position in which it is supported by all the rolls, with the members 88 now tilted to the proper supporting angle (Fig. 7). Since the supporting members are free to rotate on their shafts the rolls will remain in engagement with the surface of the coil as the diameter of the same decreases. The members 111, which are no longer held in engagement with the recesses 108 and 112 respectively, have dropped into the position shown in Fig. 7.

Fig. 8 shows the arrangement of the driving mechanism and the hydraulic system. The latter comprises a main pipe line 1 and a number of branch lines which circulate a liquid (usually oil) under pressure from a reservoir 119 feeding it to a number of pumps, where the comparatively low pressure of the liquid is converted into high pressure for driving several hydraulic mo-

tors, the function of which will be described below.

A motor for driving the rolls of the upper coil cradle is designated by 120; another motor for driving the rolls of the lower cradle by 121. 122 and 123 are pumps delivering the high pressure oil for the motors 120 and 121 respectively, both motors being provided with the usual reversing valves 124 and 125. Limit switches 126 and 127 are provided for electric control, the function of which, as has already been mentioned is to control the delivery of strip from the cradle to the flexing mechanism as described in connection with Figs. 1 and 2. The pump is set manually for speed to suit operation.

The driving mechanism for the feed rolls in the flexing device comprises a variable displacement motor 128, which is operated by a variable displacement pump 129, the action of the latter being controlled by valves 130 and 131 which are electrically actuated by solenoids E and F (Fig. 9). Several relief and check valves 132, 133, 134 are provided to prevent excess pressures and to check the operation in case of disturbances.

The slight speed change of the driving mechanism is controlled by a piston 135 slidably mounted in cylinder 136 and connected to the movable part of the motor 128 by a piston rod 137. The piston 135 is in turn controlled by an electrically operated valve 138 controlled by a solenoid G in Fig. 9.

The minimum and maximum volume of pump 129 is controlled by piston 141 slidably mounted in cylinder 140, the piston 141 being in turn governed by a valve 158 which is in communication with a measuring device, schematically shown at 178, for controlling the length of metal strip fed into the machine. Valve 158 is actuated by solenoid C. A measuring device as used here is, for instance, described in my U. S. Patent No. 2,307,777 dated January 12, 1943.

The driving mechanism of the flexing device is operated through a motor 128 by the following arrangement: On the motor shaft a pinion 138 is mounted which meshes with a gear 230 journaled on a shaft 231, which also carries a pinion 232 and a sprocket 234. The latter is connected by a chain to a sprocket 237 mounted on a shaft 36 which carries feed roll 35 of the flexing mechanism. A clutch (not shown) is provided between sprocket 237 and shaft 36, which serves for engaging or disengaging roll 35. The pinion 232 engages with a gear 238 mounted coaxially with the lower feed roll 50 of said flexing mechanism. When the machine is started the clutch between sprocket 237 and shaft 36 is set for engaging roll 35 which in turn is driven in unison with roll 50 for feeding strip into the breaker mechanism. During regular operation the drive to roll 35 is disengaged and roll 50 will do all the feeding of stock through the breaker, the breaker rolls and roll 35 are driven by the movement of the strip therethrough.

The breaker roll lifting mechanism described above is operated by a device comprising a cylinder 147 and a piston 148 slidably mounted therein. The action of this piston is controlled by a valve 148 which is electrically operated by a solenoid D (Fig. 9).

Feed rolls f and h and straightening rolls g are operatively connected with a constant displacement motor 157 whose action is controlled by valves 158 and 159 which are actuated by solenoids A and B (Fig. 9), one being a feed forward and one a feed reverse actuating means. Check

and relief valves are shown at 160 and 161 while 162 is a back check valve. The flow of the liquid under pressure in this part of the system may be seen by following the arrows in Fig. 8. It is delivered by pump 145, flows into a manifold 164, passes from there through valve 160 into the motor 157, leaves the same through the lower pipe passing through valves 161 and 162 back into the manifold 164 and through pipe o back to reservoir 119.

The adjustment of pump 145 to a minimum or maximum speed is controlled by set screws 153 and 154, 154 for slow speed and 155 for high speed. Piston rod 149 shifts pump to high or slow speed 15 at the proper time during the cycle of the feed. 150 is a part of the pump which pivots about shaft 151 to change the volume of fluid delivered. 153 is a pressure relief valve for this part of the hydraulic system.

The wiring diagram showing the electrical connections is illustrated in Fig. 9. L¹ and L² are the main lines carrying current of 440 volts from a power source to a transformer 291 where it is transformed to current of 110 volts to supply the control circuit. 292 is the primary, 293 the secondary of the transformer. Connected in the power circuit are a number of solenoids, A to H, which are adapted to be energized and to control valves for operating the hydraulic motors, as will more fully appear in the following description. Each of the solenoids has associated thereto an electromagnetic relay comprising a coil and one or more contacts, the closing of one of which will cause the energizing of the respective solenoid. 35 Which ones of the solenoids are energized at a time depends on the position of the push button switches, 258 to 266, and the limit switches M to R.

A hand starting switch 250 and a limit switch on the machine O are provided for closing the circuit which will start the operation of the complete machine. These switches are actuated after a selector switch 248, which is shown in the off position, is manually set to take one of the positions drawn in dotted lines. In case switch 248 is moved down to take the lower position, switch 250 is closed manually. A circuit will then be established with current flowing through line 280 and contact 251 to line 270 on one side of the secondary 293 and lines 312, 309, coil C² to line 262 on the other side of the secondary 293.

In the other case, with switch being moved to the upper position, the automatic switch O comes into action, the circuit being the same as outlined above.

After the machine has thus been started with the energization of coil C² all the other necessary contacts will follow in proper order.

The operation of the breaker machine during the inching period is started by pressing down button 255, which closes contact 255^a. Current will pass from the secondary 293 through line 270 over closed contacts 251, 252 and 253, contact 255^a, line 363, normally closed limit switch P, coil C⁷ and back through line 262 to secondary 293. Coil C⁷ has thus become energized and closes contacts 295, 296 and 297. Closing of contact 295 will connect L¹ over solenoid F with L² so that solenoid F will become operative actuating the valve 131 for controlling the variable displacement motor 128 forward motion. When button 255 is pressed down, coil C⁴ is de-energized causing the breaker to operate in slow speed. 70 Except at this time, and during the actuation of

reverse and stop buttons, C⁴ is always energized. The closing of contact 296 would at the same time cause energization of solenoid D over line 325 and normally closed contact 326; D is the solenoid which actuates the breaker roll lifting device. As it is not desirable to have the breaker rolls work before a strip has been fed through to roll 50, a button 324 is provided which is pressed down at the same time as button 255. A circuit is thus established from 293 over line 270, contact 251, line 238, button 324, coil C¹⁰, line 262, back to the transformer, which opens contact 326. After stock has been fed through to roll 50, button 324 is released, allowing solenoid D to become energized and causing the breaker rolls to close.

The third contact which is closed by energization of coil C⁷, viz., 297, establishes a circuit over line 298, line 265, contact 256, line 238, contact 251, line 270, secondary of transformer, line 262, coil C⁷, limit switch P and line 299 back to 297, which will be interrupted either automatically by limit switch P or manually by button 256, in case the breaker rolls ought to be stopped because of the irregularities in the feeding of the strip or for some other reason.

When the stock reaches rolls f it is inched through straightener and feed-out rolls.

By pushing button 254 down to take the position 254^a the feeding machine will start operating at slow speed as long as this button is held down. Current in this case will flow from 293 over line 270, contacts 251, 252, 253, line 274, 254^a, line 313, line 309, coil C², line 262 back to 293, energizing solenoid H which controls the resetting of the dial in the strip length measuring device. Coil C¹ is energized a slight time later by closing of contact 261, and solenoid A will become operative, which governs the constant displacement motor 157 by valve 158 and actuates the rolls f, g and h on the feed-out side of the flexing device. After buttons 254 and 255, which are pressed down at the start only, have been released, the following circuits come into action. Current flows from secondary 293 over line 270, contacts 251, 252, 253, line 274, contacts 254, 255, line 300, coil C⁴, line 262 back to secondary 293; coil C⁴ having become energized, closes contacts 268 and 269. By closing of contact 268 a circuit is established over line 257, limit switch M, through coil C¹, line 262, coil C³, limit switch N, line 271, back to contact 268. Coils C¹ and C³ remain deenergized as long as the circuit to C² is open.

By energizing coil C², contacts 261, 263 and 264 have also been closed, the latter connecting L¹ over solenoid H to L², thus energizing solenoid H and actuating the resetting dial for the strip length measuring device mentioned above. At the same time the energization of coil C³ has closed contact 279 which makes the connection of L¹ over solenoid C to L² possible, energizing solenoid C and actuating control valve 156 which positions both breaker and feed pumps to operate the machine at a predetermined rate of speed.

The closing of contact 263 causes establishment of a circuit over lines 265, 298, contact 297, line 299, line 363 back to 263, the purpose of which will appear later on.

By closing of contact 261 current is also flowing through lines 311, 308, 274 over contacts 253, 252, 251 and line 270 to secondary 293 and back through the line 262, coil C¹, limit switch M, line 310 to 261. The energization of coil C² is dependent on button 250 and C¹ is dependent on

C³. Contact 259 maintains the energization of C² and C¹, after 250 is released until the contact of limit switch M is broken.

The electric control system so far described is used principally for starting the machine and getting it into normal operation. Provisions have also been made for automatic control of the speed of the strip being fed from breaker to feed rolls. The electric means serving for the control of this part of the system comprises a circuit consisting of line 262, coil C⁹, line 323, limit switch Q, normally closed, line 267, contact 256, button 251, line 270 and secondary 293. Solenoid C⁹, which is energized, closes contact 280. This circuit and another circuit, which will be described directly hereafter, are adapted to energize and deenergize respectively a solenoid G which govern the change of speed in the driving mechanism of breaker only. As mentioned before, this solenoid actuates valve 139, which, through piston 135, controls a slight change in speed of motor 128. In case the rate of feeding of strip is too fast, limit switch R, normally open, is closed by metal strip S, hanging down and tripping said switch (Fig. 1), thereby completing a circuit from line 262, over coil C⁸, line 322, switch R, line 286, contact 280, line 281, contact 256, button 251, line 270, secondary 293 back to 262.

The energization of coil C⁸ causes contacts 282, 283 to be closed, thereby on the one hand connecting L¹ through contacts 282 through solenoid G to L², thus energizing solenoid G. On the other hand the contacts 283 provide a shunt for C⁸ to remain energized in case switch R opens again. The shunt comprises contact 283 and line 284.

If the speed of the feed rolls is becoming too slow, limit switch Q (Fig. 1) is tripped by strip S and is caused to open. In this case the flow of current is interrupted, coil C⁹ is deenergized, contact 280 is opened and the circuit for the energization of G is likewise broken. By deenergizing G the action of control valve 139 on piston 135 is reversed and speed is increased. While the circuit is momentarily interrupted by the opening of switch Q, current is still flowing from secondary 293 over line 270, button 251, contact 256, line 265 over line 298 to contact 297, lines 299, 363, contact 263, back to the other side of line 265, so that the operation of the machine remains uninterrupted.

In case it is intended to reverse the action of the feed rolls, switch 253 is pushed down to take the contact position shown in dotted lines (Fig. 9). In this case current is caused to flow from line 270 over the contacts 251, line 271, dotted line of contact 253, coil C⁵, line 262, energizing coil C⁵, which in turn closes contact 276, connecting L¹ over solenoid B to L², energizing B. The latter actuates valve 159 (Fig. 8) which controls motor 157 and reverses its action.

In a similar manner the direction of motor 128 may be reversed by energizing solenoid E. For this purpose the button of contact 252 is pressed down to take the position shown in dotted lines, current flowing from line 270 over contact 251, line 272, coil C⁸ to line 262, contact 273 being closed, solenoid E being energized, actuating valve 130 for the control of motor 128 (Fig. 8).

Apart from the switches already mentioned the circuit may be broken and the operation of the machine as a whole interrupted by opening contact 251, being in line 270, which is one of the main lines for connecting the secondary 293

of the transformer, whereas the opening of contact 256 will only stop the breaker.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a metal strip feeding mechanism in combination a pair of adjustable coil cradles, a flexing device for the metal strip, said flexing device comprising a plurality of guide rolls and two sets of breaker rolls, one mounted above the other, the lower set of said breaker rolls being pivotally mounted to be capable of swinging downward to open up a passageway for introducing the metal strip before starting the flexing operation, means for alternately feeding the metal strip from one of said coil cradles to and through said flexing device, a plurality of limit switches controlling the speed during the passage through said flexing device, hydraulic power means for operating said feeding mechanism and electric control means for said hydraulic means.

2. In a metal strip feeding mechanism in combination a pair of coil cradles, a flexing device for the metal strip, said flexing device comprising a plurality of guide rolls and two sets of adjustable breaker rolls, means for feeding the metal strip from said coil cradles to and through said flexing device, guiding means for guiding said strip as it leaves the flexing mechanism, said guiding means comprising a movable bar adapted to be lifted into engagement with said strip each time the feeding of strip is started, electric means for controlling the speed of said metal strip on its way to said flexing device and electric means controlling the speed during the passage through said flexing device, hydraulic power means for operating said feeding mechanism and electric control means for said hydraulic means.

3. In a metal strip feeding mechanism in combination, a pair of adjustable coil cradles, part of the adjusting mechanism being automatic and part of it being separately operated, a flexing device for the metal strip, said flexing device comprising a plurality of guide rolls and a double set of breaker rolls, means for feeding the metal strip from said coil cradles to said flexing device, a plurality of electric means for controlling the speed of said metal strip on its passage to and through said flexing device, other electric means for interrupting the feed after the measured length of strip has been operated on, a plurality of pumps and hydraulic motor units for operating said feeding mechanism and electric control means for said pumps and hydraulic motors.

4. In a metal strip feeding mechanism in combination a coil cradle, a conditioning device for the metal strip, means for feeding the metal strip from said coil cradle to said conditioning device, through and out of the same, means for controlling the speed of said metal strip on its entire passage through said mechanism and hydraulic power means for operating said feeding mechanism, said hydraulic power means comprising a pump-motor unit for driving said coil cradle, a pump-motor unit for driving the rolls of the conditioning device and valves associated with said pump-motor unit to control the direction and the speed of said motors.

5. In a metal strip feeding mechanism in combination an upper coil cradle and a lower coil

cradle, a flexing device for the metal strip, means for feeding the metal strip from said coil cradles to said flexing device, electric means for controlling the speed of said metal strip to the flexing device and on its passage therethrough and hydraulic power means for operating said feeding mechanism, said hydraulic power means comprising a pump-motor unit for the upper coil cradle, a pump-motor unit for the lower coil cradle, electric control means for regulating the operation of said units, a variable displacement motor for driving the rolls of said flexing device, valves for reversing the motor action, another valve controlling the speed of said motor, and electric control means for actuating all of said valves.

6. In a metal strip feeding mechanism in combination an upper coil cradle and a lower coil cradle, a flexing device for the metal strip, means for feeding metal strip from said coil cradles to said flexing device, said flexing device comprising a plurality of feed rolls and two sets of breaker rolls one mounted above the other, an adjusting mechanism for the lower set of breaker rolls and hydraulic power means for operating said feeding mechanism, said hydraulic power means comprising a pump-motor unit for the upper coil cradle, a pump-motor unit for the lower coil cradle, electric control means for regulating the operation of said units, a variable displacement motor for driving the rolls of said flexing device and valves for reversing the motor action, another valve controlling the speed of said motor and electric control means for actuating said valves, and actuating means for said breaker roll adjusting mechanism.

7. In a metal strip feeding mechanism in combination an upper coil cradle and a lower coil cradle, a flexing device for the metal strip, means for feeding metal strip from said coil cradles to said flexing device, said flexing device comprising a plurality of feed rolls and two sets of breaker rolls one mounted above the other, an adjusting mechanism for the lower set of breaker rolls and hydraulic power means for operating said feeding mechanism, said hydraulic power means comprising a pump-motor unit for the upper coil cradle, a pump-motor unit for the lower coil cradle, a pump-motor unit for driving the feed rolls and the breaker rolls of said flexing device, an electrically controlled actuating means for said breaker roll adjusting mechanism and control valves for the setting of a feed device for a measured length of strip.

8. In a metal strip feeding mechanism in combination an upper coil cradle and a lower coil cradle, a flexing device for the metal strip, means for feeding a measured length of metal strip from said coil cradles through said flexing device, said flexing device comprising a plurality of feed rolls and two sets of breaker rolls one mounted above the other, an adjusting mechanism for the lower set of breaker rolls, a plurality of feed-out rolls at the delivery side of said flexing device, and hydraulic power means for operating said feeding mechanism, said hydraulic power means comprising a pump-motor unit for the upper coil cradle, a pump-motor unit for the lower coil cradle, electric control means for regulating the speed of said units, a variable displacement motor for driving the rolls of said flexing device and one pair of valves for reversing the motor action, another valve controlling the speed of said motor and electric control means for actuating said valves, actuating means

for said breaker roll adjusting mechanism, and a constant displacement motor for driving the feed-out rolls of the flexing device.

9. In a metal strip feeding mechanism in combination a coil cradle, a conditioning device for the metal strip, means for feeding the metal strip from said coil cradle to said conditioning device, through and out of the same, hydraulic power means for operating said feeding mechanism, and electric means for controlling the speed of said metal strip on its entire passage through said mechanism, said electric means comprising a power circuit, a transformer, a plurality of auxiliary circuits, including a secondary of said transformer, for closing said power circuit, a plurality of solenoids in said power circuit controlled from said auxiliary circuits, said solenoids being adapted to actuate valves in said hydraulic power means and thereby to control the operation of said hydraulic power means.

10. In a metal strip feeding mechanism in combination a coil cradle, a conditioning device for the metal strip, means for feeding the metal strip from said coil cradle to said conditioning device, through, and out of the same, hydraulic power means for operating said feeding mechanism, said hydraulic power means comprising a pump-motor unit for driving said coil cradle, a pump-motor unit for driving the rolls of the conditioning device, another pump-motor unit for driving feed-out rolls at the delivery side of said conditioning device, control valves associated with the two last-mentioned pump-motor units, and electric means for controlling the hydraulic system, said electric means comprising a power circuit, a transformer, a plurality of auxiliary circuits, including a secondary of said transformer for closing said power circuit, a plurality of solenoids in said power circuit, said solenoids being adapted to actuate said valves in said hydraulic power means and thereby to control the operation of said hydraulic power means.

11. In a metal strip feeding mechanism in combination an upper coil cradle and a lower coil cradle, a flexing device for the metal strip, means for alternately feeding the metal strip from one of said coil cradles to said flexing device, hydraulic power means for operating said feeding mechanism, said hydraulic power means comprising a pump-motor unit for the upper coil cradle, a pump-motor unit for the lower coil cradle, limit switches for regulating the speed of said units, a pump-motor unit for driving the rolls of said flexing device, valves for governing the direction of said motor, another valve controlling the speed of said motor and electric control means for actuating said valves, said electric means comprising a power circuit, a transformer, a plurality of auxiliary circuits including the secondary of said transformer, for closing said power circuit, one of said auxiliary circuits comprising a solenoid adapted to actuate the valve for motor action in forward direction, another of said auxiliary circuits comprising a solenoid adapted to actuate the valve for reverse motor action, a third auxiliary circuit comprising a solenoid adapted to actuate the speed control valve.

12. In a metal feeding mechanism in combination an upper coil cradle and a lower coil cradle, a flexing device for the metal strip, means for alternately feeding the metal strip from one of said coil cradles to said flexing device, a breaker roll adjusting mechanism associated with said flexing mechanism, feed-out rolls at the delivery

side of the flexing device, hydraulic power means for operating said feeding mechanism, said hydraulic power means comprising a pump-motor unit for the upper coil cradle, a pump-motor unit

5 for the lower coil cradle, electric control means for regulating the speed of said units, a variable displacement motor for driving the rolls of said flexing device, a pair of valves for governing the direction of the motor, another valve controlling the speed of said motor, a constant displacement pump-motor unit for driving the feed-out rolls, valves for controlling the direction of said feed-out rolls, a valve for controlling said breaker roll adjusting mechanism, and electric means for actuating said valves, said electric means comprising a power circuit, a transformer, a plurality of auxiliary circuits including the secondary of said transformer for closing said power circuit, one of said auxiliary circuits comprising a solenoid adapted to actuate the valve for motor action in forward direction, another of said auxiliary circuits comprising a solenoid actuating the valve for reverse motor action, another of said auxiliary circuits comprising a solenoid adapted to actuate said valve for controlling said breaker roll adjusting mechanism in unison with said motor action in forward direction.

13. In a metal strip feeding mechanism in combination an upper coil cradle and a lower coil cradle, a flexing device for the metal strip, means for alternately feeding the metal strip from one of said coil cradles to said flexing device, hydraulic power means for operating said feeding mechanism, said hydraulic power means comprising a pump-motor unit for the upper coil cradle, a pump-motor unit for the lower coil cradle, limit switches for regulating the speed of said units, a pump-motor unit for driving the rolls of said flexing device, a pump-motor unit for driving the feed-out rolls at the delivery side of said flexing device, valves for governing the direction of the two last mentioned motors, another valve controlling the speed of said motor for driving the rolls in said flexing device and electric control means for actuating said valves, said electric means comprising a power circuit, a transformer, a plurality of auxiliary circuits including the secondary of said transformer for closing said power circuit, two of said auxiliary circuits comprising a solenoid each adapted to actuate the valves for motor action in forward direction, two others of said auxiliary circuits comprising a solenoid each adapted to actuate the valves for reverse motor action, and another auxiliary circuit comprising a solenoid adapted to actuate the speed control valve.

14. In a metal feeding mechanism in combination an upper coil cradle and a lower coil cradle, a flexing device for the metal strip, means for feeding a measured length of the metal strip from said coil cradles to said flexing device, means for setting the measuring device for said strip length, feed-out rolls at the delivery side of the flexing device, hydraulic power means for operating said feeding mechanism, said hydraulic power means comprising a pump-motor unit for the upper coil cradle, a pump-motor unit for the lower coil cradle, limit switches for regulating the speed of said units, a variable displacement motor for driving the rolls of said flexing device, a pair of valves for governing the direction of said motor, another valve controlling the speed of said motor, a constant displacement pump-motor unit for driving the feed-out rolls, valves for controlling the direction of said feed-out rolls, a valve for

controlling the setting means for the strip length measuring device and electric means for actuating said valves, said electric means comprising a power circuit, a transformer, a plurality of auxiliary circuits including the secondary of said transformer for closing said power circuit, two of said auxiliary circuits comprising a solenoid each adapted to actuate the valves for motor action in forward direction, two others of said auxiliary circuits comprising a solenoid each adapted to control reverse motor action, and two other auxiliary circuits comprising a solenoid each, one for controlling the setting and the other the driving of the strip length measuring device.

15. In a metal strip feeding mechanism in combination, an upper coil cradle and a lower coil cradle, a flexing device for the metal strip, means for feeding strip from said coil cradles to said flexing device, pivotally mounted means in said flexing device adapted alternately to engage a metal strip from said upper or lower coil cradle respectively when it is fed to the flexing device, said flexing device comprising a plurality of guide rolls and two sets of breaker rolls, means for feeding the metal strip through said flexing device, electric means including a plurality of limit switches for controlling the speed of said metal strip through said flexing device, hydraulic power means for operating said feeding mechanism and electric control means for said hydraulic means.

16. In a metal strip feeding mechanism in combination a pair of adjustable coil cradles, a flexing device for the metal strip, said flexing device comprising a plurality of guide rolls and two sets of breaker rolls, one mounted above the other, the lower set of said breaker rolls being mounted to open up a passageway for introducing the metal strip before starting the flexing operation, means for alternately feeding the metal strip from one of said coil cradles to and through said flexing device, electric means for controlling the speed of said metal strip on its way to and through said flexing device and hydraulic power means for operating said feeding mechanism and electric control means for said hydraulic means.

17. In a metal strip feeding mechanism in combination a pair of adjustable coil cradles, a flexing device for the metal strip, said flexing device comprising a plurality of guide rolls and two sets of breaker rolls, one of said guide rolls having a guide shoe pivotally mounted to cooperate therewith in the initial feeding of said strip and capable of being cammed out of said cooperating position during a period of continuous feeding, means for alternately feeding the metal strip from one of said coil cradles to and through said flexing device, electric means for controlling the speed of said metal strip on its way to said flexing device and a plurality of limit switches controlling the speed during the passage through said flexing device, hydraulic power means for operating said feeding mechanism and electric control means for said hydraulic means.

18. In a metal strip feeding mechanism in combination a pair of adjustable coil cradles, a flexing device for the metal strip, said flexing device comprising a plurality of guide rolls and two sets of breaker rolls, one mounted above the other, the lower set of said breaker rolls being mounted to open up a passageway for introducing the metal strip before starting the flexing operation, means for alternately feeding the metal strip from one of said coil cradles to and through said flexing device, piston operated means for actuating said lower set of breaker rolls in timed relation with

the feed of metal strip, electric means for controlling the speed of said metal strip on its way to said flexing device and a plurality of limit switches controlling the speed during the passage through said flexing device, hydraulic power means for operating said feeding mechanism and electric control means for said hydraulic means.

19. In a metal strip feeding mechanism in combination a pair of adjustable coil cradles, a flexing device for the metal strip, said flexing device comprising a plurality of guide rolls and two sets of breaker rolls, means for alternately feeding a measured length of the metal strip from one of said coil cradles to and through said flexing device, guiding means for guiding the strip as it leaves the flexing mechanism before it reaches successive gripping rolls, electric means for controlling the speed of said metal strip on its way to said flexing device and a plurality of limit switches controlling the speed during the passage through said flexing device, hydraulic power means for operating said feeding mechanism and electric control means for said hydraulic means.

20. In a metal strip feeding mechanism comprising hydraulic power means for operating said mechanism and electric control means for said hydraulic means, in combination, a coil cradle comprising a pair of parallel supporting and driving shafts, tubes to receive said driving shafts over parts of their length, means to rotatably support the ends of said driving shafts, a plurality of carrying members on said supporting shafts and on said tubes respectively, mounted for rocking movement on their supports, each of said carrying members being adapted to rotatably support a pair of roll carrying shafts, and power transmission means between all of said shafts whereby rotation of the driving shafts and the roll carrying shafts will occur simultaneously.

21. In a metal strip feeding mechanism comprising power means for driving said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said tubes respectively mounted for rocking movement on their supports, each of said carrying members being adapted to rotatably support a pair of roll carrying shafts, rolls on said last mentioned shafts adapted to rock with said carrying members while being rotated on said roll carrying shafts and power transmission means between all of said shafts whereby rotation of the driving shafts and the roll carrying shafts will occur simultaneously.

22. In a metal strip feeding mechanism comprising power means for operating said mechanism, in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said tubes respectively mounted for rocking movement on their supports, each of said carrying members being adapted to rotatably support a pair of roll carrying shafts, rolls on said last mentioned shafts adapted to rock with said carrying members, and a coil guiding member mounted to pivot about the one of said supporting shafts adapted to perform a rocking movement and to lie in alignment with a

platform of the machine frame for receiving a coil at the time the cradle is loaded.

23. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll carrying shafts, rolls on said last mentioned shafts adapted to rock with said carrying members, a coil guiding member pivotally mounted on the one of said supporting tubes nearer to the coil receiving side of the cradle, said coil guiding member being adapted to perform a rocking movement independently of the rocking movement of the carrying members and adapted to lie in alignment with a platform of the machine frame for receiving the coil at the time the cradle is loaded.

24. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll carrying shafts, rolls on said last mentioned shafts adapted to rock with said carrying members, two coil guiding members one mounted to pivot about the one of said supporting shafts nearer to the coil receiving side of the cradle and the other mounted on the one of the supporting tubes on said side, said coil guiding members being adapted to perform a rocking movement independently of the rocking movement of the carrying members, and to lie in alignment with a platform of the machine frame in shoulders formed on said frame for receiving the coil at the time the cradle is loaded.

25. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll carrying shafts, rolls on said last mentioned shafts adapted to rock with said carrying members, two coil guiding members one mounted to pivot about the one of said supporting shafts nearer to the coil receiving side of the cradle and the other mounted on the supporting tube on said side, said coil guiding members being adapted to perform a rocking movement independently of the rocking movement of the carrying members and further adapted to lie in alignment with a platform of the machine frame while receiving the coil at the time the cradle is loaded and to be tilted to an angle and to drop from engagement with the coil surface during the operation of the machine.

26. In a metal strip feeding mechanism com-

prising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll carrying shafts, rolls on said last mentioned shafts adapted to rock with said carrying members, two coil guiding members one mounted to pivot about the one of said supporting shafts nearer to the coil receiving side of the cradle and the other mounted on the supporting tube on said side, said coil guide members being of substantially triangular shape with the apex journaled to their supports so as to perform a rocking movement independently of the rocking movement of the carrying members, and having flanges extending from each of the other corners adapted to lie in shoulders of the machine frame, an elongated platform being formed thereby on the machine frame for receiving the coil at the time the cradle is loaded.

27. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll carrying shafts, rolls on said last mentioned shafts adapted to rock with said carrying members, two coil guiding members one pivotally mounted on one of said supporting shafts nearer to the coil receiving side of the cradle and the other pivotally mounted on the supporting tube on said side, said coil guide members being substantially triangularly shaped with the apex journaled on an axis corresponding to the axis of the supporting shaft so as to perform a rocking movement independently of the rocking movement of the carrying members, and having flanges extending from each of the other corners adapted to lie in shoulders of the machine frame, an elongated platform being formed thereby on the machine frame for receiving the coil at the time the cradle is loaded, said coil-guiding members being further adapted to be tilted to an angle and drop from engagement with the surface of said coil during uncoiling.

28. In a metal strip feeding mechanism comprising hydraulic power means for operating said mechanism and electric control means for said hydraulic means in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, and a coil transfer member arranged between the cen-

tral pair of roll-carrying shafts, said transfer member comprising a vertically movable stem and a substantially horizontal top plate for temporarily receiving said coil of metal strips.

29. In a metal strip feeding mechanism comprising hydraulic power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, and two coil-transfer members symmetrically arranged between the central pair of roll-carrying shafts, each of said transfer members comprising a cylinder, a vertically movable piston in said cylinder, a substantially horizontal top plate adapted temporarily to receive said coil of metal strip and to support it during positioning of the rolls on the other side of the machine.

30. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively for rocking movement on their supports, each of said carrying members being adapted to rotatably support a pair of roll-carrying shafts, rolls on said last mentioned shafts adapted to rock with said shafts and to be rotated simultaneously with said driving shafts, and two coil-transfer members symmetrically arranged between the central pair of roll-carrying shafts, each of said transfer members comprising a cylinder, a vertically reciprocating piston responsive to liquid under pressure in said cylinder, a horizontal top member on said piston, said top member being slightly concave for receiving said coil of metal strip when the piston is in the extended position.

31. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, two coil-transfer members symmetrically arranged between the central pair of roll-carrying shafts, each of said transfer members comprising a cylinder, a vertically reciprocating piston responsive to liquid under pressure in said cylinder, a horizontal top member on said piston, said top member being slightly concave and having a shoulder formed therein for receiving a flange of a coil guiding member, said coil guiding member having a flat top part adapted to lie in substantial alignment with said

horizontal top member of said piston on one side and with a platform of the machine frame on the other side thereby forming an extended platform for transfer of the coil to the coil cradle.

32. In a metal strip feeding mechanism comprising hydraulic power means for operating said mechanism and electric control means for said hydraulic means in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, and two coil-transfer members symmetrically arranged between the central pair of roll-carrying shafts, each of said transfer members comprising a cylinder, a vertically reciprocating piston responsive to liquid under pressure in said cylinder, a horizontal top member on said piston, said top member being slightly concave and having a shoulder formed therein for receiving a flange of a coil guiding member, each of said coil guiding members having a flat top part adapted to lie in substantial alignment with said horizontal top member of said piston on one side and with a platform of the machine frame on the other side thereby forming an extended platform for transfer of the coil to the coil cradle at the time the cradle is loaded, one of said coil guiding members being journaled on one of the supporting shafts and the other on one of the supporting tubes and each coil guiding member being adapted to be tilted to an angle and to drop from engagement with the surface of said coil during uncoiling.

33. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll carrying shafts, rolls on said last mentioned shafts adapted to rock with said carrying members while being rotated on said roll carrying shafts and power transmission means between all of said shafts whereby rotation of the driving shafts and the roll carrying shafts will occur simultaneously.

34. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll carrying shafts, rolls on said last mentioned shafts adapted to rock with said carrying members, and a coil guiding member mounted to pivot about the one of said supporting shafts adapted to lie in alignment

with a platform of the machine frame for receiving a coil at the time the cradle is loaded.

35. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, and a coil transfer member arranged between the central pair of roll-carrying shafts, said transfer member comprising a vertically movable element and a substantially horizontal top plate for temporarily receiving said coil of metal strips.

36. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, and two coil-transfer members symmetrically arranged between the central pair of roll carrying shafts, each of said transfer members comprising a cylinder, a vertically movable piston in said cylinder, a substantially horizontal top plate adapted temporarily to receive said coil of metal strip and to support it during positioning on the rolls on the other side of the machine.

37. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, and two coil-transfer members symmetrically arranged between the central pair of roll-carrying shafts, each of said transfer members comprising a cylinder, a vertically reciprocating piston responsive to liquid under pressure in said cylinder, a horizontal top member on said piston, said top member being slightly concave for receiving said coil of metal strip when the piston is in the extended position.

38. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, two coil-transfer members symmetrically arranged between the central pair of roll-carrying shafts, each of said transfer members comprising a cylinder, a vertically reciprocating piston responsive to liquid under pressure in said cylinder, a horizontal top member on said piston, said top member being slightly concave and having a shoulder formed therein for receiving a flange of a coil guiding member, said coil-guiding member having a flat top part adapted to lie in substantial alignment with said horizontal top member of said piston on one side and with a platform of the machine frame on the other side thereby forming an extended platform for transfer of the coil to the coil cradle.
39. In a metal strip feeding mechanism comprising power means for operating said mechanism in combination, a coil cradle comprising a pair of parallel supporting and driving shafts, supporting tubes to receive said driving shafts over parts of their length, means to rotatably support the ends of said driving shafts, a plurality of carrying members on said supporting shafts and on said supporting tubes respectively mounted for rocking movement on their supports, each of said carrying members being adapted to rotatably support a pair of roll-carrying shafts, rolls on said last mentioned shafts adapted to rock with said shafts and to be rotated simultaneously with said driving shafts, and two coil-transfer members symmetrically arranged between the central pair of roll-carrying shafts, each of said transfer members comprising a cylinder, a vertically reciprocating piston responsive to liquid under pressure in said cylinder, a horizontal top member on said piston, said top member being slightly concave and having a shoulder formed therein for receiving a flange of a coil guiding member, each of said coil guiding members having a flat top part adapted to lie in substantial alignment with said horizontal top member of said piston on one side and with a platform of the machine frame on the other side thereby forming an extended platform for transfer of the coil to the coil cradle at the time the cradle is loaded, one of said coil guiding members being journaled on one of the supporting shafts and the other on one of the supporting tubes and each coil guiding member being adapted to be tilted to an angle and to drop from engagement with the surface of said coil during uncoiling.
